CONTAINER FORMING AND FILLING
MACHINEMichael J. Milmoe, Chicago, Ill., assignor to F. B.
Redington Co., Chicago, Ill., a corporation of
Illinois

Application December 11, 1929, Serial No. 413,338

43 Claims.

(CL. 93—3)

The present invention relates to wrapping machines and the embodiment shown in the drawings was particularly designed for wrapping toothbrushes.

5 One object of this invention is to provide an improved wrapping machine for wrapping toothbrushes in hollow tubular containers which may be made of any suitable material, but in general such tubular containers are made of paper, and particularly transparent paper or other transparent material.

At the present time it is rather common practice to wrap articles with transparent cellulose compound materials so that the article which is wrapped may be visible through the material and at the same time protected against dust and dirt which has a tendency to collect on the articles while the same are being shipped or while they are on display.

20 The wrapped articles may, if desired, be placed within a second container such as a carton having flaps at the opposite ends thereof for closing the carton. However, the present invention relates merely to wrapping the article in a dust-proof container, it being understood that the article may, if desired, thereafter be placed in a second container.

Another object of this invention is to provide a wrapping machine which utilizes blanks which are automatically formed into a container by the machine.

The means for forming the blanks into suitable containers, includes means for alining the blanks into a position adjacent the container forming mechanism, such alining means being of novel form as will be hereinafter pointed out.

Another object of this invention is the provision of a machine in which the containers are slipped over the articles as said articles are moved along a predetermined path. In ordinary machines of this nature, the article is moved into the container, but in the present device it is more practical to provide means for moving the container over the article in view of the fact that the container can be slipped off the form directly over the article, whereas if the article were to be moved into the container, it would be necessary to strip the container off the form and position it at a place where the article could be received thereby, thereby making it necessary to provide an additional operation in the packaging of the article.

Another object of this invention is to provide an improved form of means for sealing the open ends of the container. The means for sealing the

ends of the container includes means for forming preliminary folds in the ends of the container, placing a small quantity of glue in the folds, and thereafter producing additional folds in the ends of the container in such a manner as to cause the glue to at least partially seal the open ends of the container and hold the folds in proper position.

A more specific object of this invention resides in providing a glue applying means for applying the glue at selected positions with respect to the folds and in predetermined amounts.

Another object of this invention resides in providing means for producing a double fold in each of the ends of the container to more securely hold the material of the said ends in position to close the open ends of the container.

Another object of this invention is to provide an improved means for creasing the folds of the wrapper, thus insuring that the folds will be properly maintained in the wrapper while the succeeding operations take place.

Another object of this invention is to curve or otherwise distort the double fold produced at the ends of the containers and in substantially the direction of the double fold. This assists in holding the portions of the double fold in abutting relationship with each other without the necessity of special holding or sealing means for this purpose; at least this operation causes the portions of the double fold to more nearly occupy their intended positions than is possible with a straight fold which is not curved or crimped.

Still another object of this invention is to provide an improved means for folding the opposite ends of the container to produce double folds in each end by means which operates first to produce a partial fold and immediately thereafter produces the complete fold by substantially the same movement of the parts comprising this folding means.

40 Another object of this invention resides in the means for stripping the containers off the former after the containers have been formed, said means comprising a member which not only tends to move the containers off the former, but also tends to seal the overlapping edges of the containers together, a layer of glue having been applied to one of said edges prior to forming the containers from the blanks.

Another object of this invention is to provide an auxiliary means for assisting the means referred to in the previous paragraph, this latter means causing the last portion of the movement of the container off the former and into alined position over the article being wrapped.

40

50

55

Other objects of this invention will appear as the description of the apparatus shown in the drawings proceeds.

In the drawings—

5 Fig. 1 represents a front elevational view of a machine embodying my invention, with parts of the frame of the machine broken away to show various parts of the actuating mechanism;

10 Fig. 2 is a plan view of the device shown in Fig. 1;

Fig. 3 is an end elevational view of the device shown in Fig. 1 and looking from the left in that figure, part of the framework being broken away in this figure for the sake of clearness;

15 Fig. 4 is a fragmentary view of the means for alining the blanks adjacent the former;

Fig. 5 is a view of a container formed by the machine shown in the drawings;

20 Fig. 6 is a fragmentary plan view showing the manner in which the cartons are moved off the former and over the articles as they are positioned adjacent the former;

25 Figs. 7 and 8 are views similar to Fig. 6, showing the parts in different positions of adjustment;

Fig. 9 is an isometric view showing the former and the means for moving the container off the former after the same has been formed thereon;

30 Figs. 10, 11, and 12 are fragmentary elevational views of the means for wrapping or folding the blank about the former;

Fig. 13 is a fragmentary plan view similar to Fig. 6, showing the parts in a different position of adjustment;

35 Figs. 14 and 15 are fragmentary vertical sectional views showing the means for moving the container off the former;

Fig. 16 is a vertical section taken substantially on the line 16—16 of Fig. 1;

40 Figs. 17 and 18 are fragmentary plan views of the apparatus shown in Fig. 16;

Fig. 19 is a section taken on the line 19—19 of Fig. 16;

45 Fig. 20 is a fragmentary isometric view of a portion of the apparatus shown in Figs. 16 to 19, inclusive, and this view more clearly illustrates the first operation in folding the opposite ends of a container;

50 Figs. 21 to 24, inclusive, illustrate the various shapes given to the container at various stages in its passage through the machine;

Fig. 25 is a section taken substantially on the line 25—25 of Fig. 1;

55 Fig. 26 is a view similar to Fig. 25, showing the parts in a slightly different position of adjustment;

Fig. 27 illustrates the manner in which the glue is applied to the crease in one of the folds formed in the end of the container;

60 Fig. 28 is a plan view of the mechanism shown in Fig. 25;

Fig. 29 is a view similar to Fig. 28, showing the parts in a slightly different position of adjustment;

65 Fig. 30 is a plan view of the means shown in Fig. 27;

Fig. 31 is a fragmentary plan view of the mechanism for producing the double fold in the end of the container;

70 Fig. 32 is a section taken substantially on the line 32—32 of Fig. 31;

Fig. 33 is an isometric view of certain of the parts shown in Fig. 31;

75 Figs. 34 and 35 are views similar to Fig. 31, showing a portion of the parts illustrated in that

figure and with said parts in different positions of adjustment;

Fig. 36 is a view similar to Fig. 31, with the parts shown in different positions;

Fig. 37 is a detail view of certain of the parts shown in Fig. 36, said parts being shown in a different position than shown in Fig. 36;

Fig. 38 is a front elevational view of the parts shown in Figs. 31 to 37, inclusive; and

Fig. 39 is a side elevation of the driving mechanism for the blank feeding means.

Referring more particularly to Figs. 1, 2, 3, 4, and 39, it will be noted that the wrapping machine comprises a frame having a table portion 1 supported by a web 2 which extends in a vertical direction substantially centrally of the longitudinal dimension of the table 1, and reinforcing members 3 and 4 extend along opposite ends of the web 2 and act as braces for the frame. The frame is provided with a base portion 5 by which the frame is supported. The table 1 is provided with a rearward extension 6 shown in Fig. 3, and this supports a hopper 7 which is adapted to contain the blanks 8 from which the containers are formed, these blanks being substantially rectangular in form, thus making it unnecessary to cut blanks of irregular shape in order to produce the desired type of container. The means for feeding the blanks out of the hopper is of a well-known type which is shown here purely for the purpose of illustration and there is no invention claimed in the particular means for feeding the blanks out of the hopper. If desired, the blanks could be fed by hand instead of by automatic means.

35 The hopper 1 is provided with a transverse shaft 9 driven by means of a chain 10 trained over a suitable sprocket 9' on the end of the shaft 9, the chain being driven from the main drive shaft 11 as illustrated in Figs. 2 and 3. The chain 10 is also trained over a sprocket 10' on the end of the stub shaft 12' for a purpose which will be described later.

40 The shaft 9 carries a starter roll 13 provided with a small piece of friction material 14 which extends partially about the periphery of the roller 13. The friction roller 13 is arranged beneath the stack of blanks in the hopper 7 and the piece of friction material 14 is adapted to engage the lowermost blank and move the same out of the hopper, or to the right as shown in Fig. 3. This carries the blank between the opposed rollers 15 and 16.

45 The rollers 16 are secured to a shaft 17, which in turn is supported in the bracket 18 secured to the upper surface of the table 1. The arm 19 is supported on the shaft 9 and carries the other end of the shaft 17. The rollers 15 are rigidly supported upon the shaft 20 and this shaft is rotatably supported on the pivoted arms 21 and 22 as best illustrated in Fig. 2. A spring 23 is connected at its upper end to the arm 22 and at its lower end to a fixed pin on the hopper 7. This spring tends to rotate the arms 21 and 22 in a clockwise direction as viewed in Fig. 3, so as to bring the rollers 15 into engagement with the rollers 16, the roller 15 being driven by means of a gear 24 fixed to the shaft 20 and meshing with a similar gear mounted on the shaft 17, said last-mentioned gear being located directly below the gear 24.

50 The shaft 17 is driven by means of a train of gears comprising the gear 25 mounted on the shaft 9, the idler gear 26 mounted on the shaft 26', gear 25' mounted on the shaft 26' and caused 75

to rotate in unison with the gear 26 and gear 17' on the shaft 17.

Referring now more particularly to Fig. 4, it will be noted that the rollers 15 and 16 come into engagement with each other substantially on a line with the upper surface 21 of the plate 28 supported on the bracket 29, which in turn is supported on the table 1. After the blanks are moved out of the hopper 7 and between the rollers 15 and 16, the same are fed along the upper surface of the plate 28. A glue-box 30 is supported upon the upper surface of the bracket 29.

A screw 32 passes through a suitable opening in the lug 33 and is screw-threaded in the boss 34 on the bracket 29. The lug 33 is secured to the shaft 31 which extends through the glue-box and actuates a suitable scraper (not shown) for scraping the glue off the gluing wheel 37 secured to the shaft 36. The position of adjustment of the scraper may be varied by the screw 32 and the lug 33 may be actuated by any suitable mechanism (not shown) for moving the lug in the other direction against the action of the spring 35. This movement of the scraper throws the scraper 20 into engagement with the gluing wheel. The shaft 36 is connected by means of the releasable driving connection 38 to the shaft 12 supported in suitable bearings in the brackets 18 and 36'.

The brackets 36' and 18 also rotatably support a shaft 41 and is driven from the gear 43 on the shaft 12 by means of the idler gears 39 and 39' interposed between the gear 41' on the shaft 41 and the gear 43, it being understood that the idler gears are rotatably supported on suitable stub shafts mounted in the bracket 18. The shaft 12 is driven from the stub shaft 12' by means of the gear 40 which is secured to the shaft 12' and the gear 42 secured to the shaft 12. The chain 10 drives the sprocket 10' and as a result the gear 40 and the other gears are driven from the gear in the manner just described.

The shaft 12 also carries the arm 44 freely rotatable thereon and a shaft 45 is carried by the arm 44 and an arm 46 pivotally supported upon the bracket 29 at 47. The shaft 45 carries a pair of rollers 48 frictionally urged into engagement with similar rollers 49 on the shaft 41 by means of a spring 50 fastened to the arm 46 at one end and to the end 3 of the frame as illustrated in Fig. 3. The rollers 48 and 49 are caused to rotate in opposite directions by means of a gear 51 secured to the shaft 45 and a similar gear secured to the shaft 41 and meshing with the gear 51.

Thus it will be seen that as the blanks are fed out of the hopper 7 they are positioned between the rollers 15 and 16 which feed the blanks beneath the gluing wheel 37 to a position between the rollers 48 and 49, the rollers 48 and 49 forming means for feeding the blanks still further along the plate 28 into a position beneath the former 52. It is to be understood that the gluing wheel 37 is arranged within a slot which is partly in the forward edge of the glue-box and partly in the bottom thereof, the gluing wheel having a very close fit with the edges of the slot so that when the apparatus is idle no glue will leak through between the gluing wheel and the edges of the slot. However, the fit is not close enough to interfere with a small amount of the glue passing between the periphery of the wheel and the adjacent edge of the slot. In other words, the slot acts as a scraping means for predetermining the amount of glue to remain on the periphery of the wheel and also acts to prevent leakage of the glue out of the glue-box. The glue on the gluing wheel

is deposited along one edge of the blanks 8 which are fed therebeneath.

The former 52 is located in advance of the rollers 48 and 49 and in view of the fact that the rollers 48 and 49 do not move the blank forward quite far enough to position the same in proper position beneath the former 52, it becomes necessary to provide additional means to position the blank in proper position beneath the former 52. This additional means not only is designed for the purpose of moving the blank forward, but also designed to align the blank or "square" the blank relatively to the former 52. This means is best illustrated in Figs. 3, 4, and 6 and comprises a member 53 pivoted at 54 to the bracket 29 and 15 provided with a pair of fingers 55 secured thereto. The member 53 is adapted to be moved from the full line position to the dotted line position shown in Fig. 4. In the latter position, the forward edges of the fingers 55 are located below the surface of the plate 28 and permit the blank to be fed thereover without interference by the fingers. After the blank has been fed between the adjacent surfaces of the rollers 48 and 49, the member 53 is moved from the dotted line position to the full line position illustrated in Fig. 4 and the notches 56 in the forward edges of the fingers 55 engage the rear edge of the blank and move the same forward to a position below the former 52 and in proper position with respect thereto. 30

A link 57 is pivoted at 58 to the member 53 and is also pivoted at 59 to an arm 60 rotatably supported upon the shaft 61 and adapted to be rocked about the shaft 61 by means of a cam mounted on the shaft 11, there being a cam and a cam groove connection between the arm 60 and a cam similar to that shown for the arm 62 in Fig. 3. This cam construction is well known in the art to which this invention pertains and no further illustration thereof is thought to be necessary. 40

Oscillation of the arm 60 causes the member 53 to be rocked about its pivot 54 for the purposes set forth, it being understood that the cams on the shaft 11 are so arranged as to bring the fingers 55 into operative position after the blank has moved past the forward edge of the fingers 55, and preferably after the blank has passed between the rollers 48 and 49. It will be noted in Fig. 6 that the fingers are spaced apart and this is for the purpose of permitting the fingers to pass between the shafts 45 and 41 and between the side faces of the rollers 48 and 49 which are spaced longitudinally of the shafts 45 and 41, respectively. 50

So far the description has had to do with the feeding of the blank to a position beneath the former 52. I will now proceed to describe the means for forming the container by means of suitable forming or folding devices which fold the blanks about the former 52 so that the opposite edges of the blanks are in overlapping relation and with the glue between the overlapping edges. 55

The means for forming the hollow container are best illustrated in Figs. 1, 10, 11, 12, 14, and 15. The folding devices are carried by three arms 63, 64 and 65 pivoted at 66, 67, and 68, respectively to a bracket 69. The arms 63, 64, and 65 each form an arm of a bell-crank, the other arms being 60 designated 70, 71, and 72, respectively. The bell crank comprising the arms 70 and 63 is connected by means of a link 73 to an arm 74 pivoted to a shaft 75. The arm 74 carries a suitable cam roller for engaging a cam 74' on the shaft 76 75

driven by means of the beveled gears 77 and 78 from the main drive shaft 11. The cam rocks the arm 74 and thereby rocks the arms 70 and 63 about the pivot 66 in proper timed relation to the movements of the other parts of the machine and for the purposes hereinafter to be described. Similarly the arm 71 is connected by means of a link 79 to an arm 80 pivoted on the shaft 75, the arm 80 being actuated by a suitable cam (not shown) located on the shaft 76, it being understood that different cams are used for rocking the arms 74 and 80. The arm 72 is connected by means of a rod 81 to the free end of the lever 82 shown in Fig. 3, said lever being pivotally mounted on the shaft 61 and having a suitable roller 83 adapted to engage the cam 84 on the shaft 11.

The rod 81 extends through a suitable enlarged opening in the end of the lever 82 and a spring 85 abutting the collar 84 tends to hold the enlarged end 86 of the rod 81 against the under side of the arm 82. This connection enables the rotating movement of the arm 82 to be transmitted to the rod 81 without causing the rod 81 to bind within the recess in the end of the arm. By the means just described, the arms 63, 64, and 65 are moved in proper timed relation to each other. This timed relation brings the folding elements into successive operation in a manner which I will now proceed to describe.

30 The plate 28 is provided with a suitable opening 87 directly below the former 52. The former is supported by means of a bracket 88 having a dovetail connection 89 with an extension 90 on the former 52. The arm 63 carries the spaced plates 91 and 92 as best illustrated in Figs. 10, 11, and 12, the plate 92 being somewhat shorter than the plate 91. It will be understood that the plates 91 and 92 are substantially the same length as the former 52 and the blank which is to be formed into a container. The arm 63 also carries a rod 93, which in turn carries a bar 94. The rod 93 is slidably supported in the block 95 on the end of the arm 63 and is interposed between the plates 91 and 92. A spring 96 normally urges the rod into the position shown in Fig. 12. A collar 97 secured to the other end of the rod limits the movement of the rod in the direction in which it is urged by the spring 96. The surface of the bar 94 is substantially flush with the forward edge of the plate 91, but if desired, the surface of the bar 94 may be arranged slightly in advance of the forward edge of the plate 91 so that as the arm 63 moves the plates 91 and 92 and also the bar 94 through the opening 87, the bar 94 will engage the blank 8 and move the blank into engagement with the under side of the former 52 before the plates 91 and 92 begin their folding operation.

60 After the bar 94 has clamped the blank 8 against the lower side of the former 52, the plate 91 continues to move upwardly to fold the blank 8 along the left-hand side of the former 52 as viewed in Figs. 10 and 12. The plate 92 also folds a portion of the blank 8 along the right-hand side of the former 52 as best illustrated in Fig. 10, but comes into operation shortly after the plate 91 comes into operation. As the plates 91 and 92 move upwardly to fold the blank as described, the spring 96 is compressed and the rod 93 slides in the bearing block 95 to the position shown in Fig. 10.

While the arm 63 remains in the position shown in Fig. 10, the arm 65 is moved in a counter-clockwise direction about its pivot. The

arm 65 carries the folding plate 98 secured thereto by means of a bolt 99 and this plate 98 engages the upwardly extending portion of the blank 8 shown in Fig. 10 and folds this portion over the upper side of the former 52 as illustrated in Fig. 11. It is now necessary to fold the free edge of the blank 8 which extends in a horizontal position as shown in Fig. 11.

This is accomplished by means of the folding plate 100 freely slidably upon the pins 101 projecting from the arm 64. The pins 101 are surrounded by coil springs 102 which abut against the plate 100 and a collar 103 on the shaft 101. This arrangement permits the plate 100 to yield outwardly. The plate 100 is provided with an opening 104 for the purpose of receiving a roller 105 which has a friction surface 106. The action of this roller will be described presently.

As the arm 64 is rotated in a clockwise direction, the forward edge of the plate 100 engages the free edge of the blank 8 shown in Fig. 11 and moves this free edge down over that edge of the blank which is already folded against the right-hand side of the former 52 and which is being held in place by means of the plate 92. As soon as a portion of the free edge of the wrapper 8 shown in Fig. 11 is brought into engagement with that edge which is already folded against the former 52, the arms 63 begins a clockwise movement to retract the plates 91 and 92 and so as to permit the plate 100 to move into the position shown in Fig. 12. It will be noted that the last edge of the blank which was brought into position over the former 52 carries the glue applied by the gluing wheel 37; therefore, the glue lies between the overlapping opposite edges of the blank 8 and the plate 100 has a tendency to force these edges toward each other and thereby seal the longitudinal seam of the hollow container. However, it is preferable to provide additional means to seal this longitudinal seam and this is accomplished by means of the roller 105 which performs a dual function, one function of which is to seal the longitudinal seam and the other of which is to move the formed container off the former 52 and into a position over the article to be packaged. Naturally the roller 105 has to be moved out of the way during the descent of the plate 100 and therefore means must be provided for this purpose.

This means is best illustrated in Figs. 1, 14, and 15. The roller 105 is carried by the shaft 107 journaled within the hollow bearing member 108 which is pivoted to a shaft 109 and connected in driving relation thereto by means of the beveled gears 110 and 111 mounted on the shafts 107 and 109, respectively. The shaft 109 carries a sprocket 112 over which is trained a chain 113, the chain also being trained over a sprocket 114 on the shaft 76. The shaft 76 also carries a suitable cam 115 having a cam groove 116 adapted to be engaged by a cam roller 117 carried by an extension on the arm 118 pivotally mounted on the shaft 76. The arm 118 is connected by means of a link 119 to the hollow sleeve 108 at 120. The hollow bearing member 108 is pivotally mounted to swing about the shaft 109. As the shaft 76 rotates, the hollow bearing member 108 and as a result the shaft 107 and roller 105 are caused to be oscillated about the shaft 109 as a pivot, thus causing the roller 105 to be moved from the position shown in Fig. 14 to the position in Fig. 15, and back again to the position shown in Fig. 14 as long as the shaft 76 continues to rotate. This movement is in timed re-

lation to the movement of the folding members carried by the arms 63, 64, and 65 and is so timed as to bring the friction surface 106 of the roller 105 into engagement with the overlapping edges 5 of the blank 8 now forming the container designated as 121 just after the plate 100 has reached the position shown in Fig. 12, the roller 105 extending through the opening 104 of the plate 100 as previously described.

10 It will be noted that the roller 105 is continuously rotated by means of the connections previously described, and this rotation is in such a direction as to move the hollow container 121 partially off the former 52, the direction of rotation 15 of the roller 105 being indicated by an arrow in Fig. 9. The container 121 is now in the form of a hollow tubular member having open ends as best illustrated in Fig. 21, and the container is now ready to receive the article to be 20 inserted therein, or more strictly speaking, to be slipped or positioned over the article while the article is held in a predetermined position.

A means is provided for positioning the articles in a predetermined position adjacent the end of 25 the former 52 and in close proximity thereto. This means comprises a pair of endless chains 122 which carry the buckets 124 having recesses 125 in their upper surfaces for receiving the articles 126, which in the present instance are 30 toothbrushes. Referring more particularly to Figs. 1 and 2, it will be noted that the chains 122 are trained over suitable sprockets 123 and 127 secured to the shafts 128 and 129, respectively.

35 The shaft 129 also carries a Geneva gear 130 and this Geneva gear is actuated in a well-known manner by means of a pin 131 on the disc 132 driven by means of the chain 133 from the shaft 76, suitable sprocket teeth being provided on the 40 disc 132 and a suitable sprocket 134 being provided on the shaft 76 for engaging the links of the chain 133. The Geneva movement gives an intermittent movement to the chains 122 and thus the buckets 124 are moved so as to occupy 45 successive positions spaced apart a distance equal to the distance between the centers of the buckets. One position of the buckets is indicated at "A" (see Figs. 6, 7, 8, and 13). A bucket located at the position "A" is arranged substantially in 50 alinement with the former 52. When the buckets 124 stop at the position "A" the roller 105 comes into operative position against the side of the container 121 and moves the container into the recess 125 in the bucket 124, the edges 55 of the buckets being beveled as at 135 to facilitate the entrance of the container into the bucket. This also enables the lower edge of the container to position itself under the article as it will be noted from an inspection of Fig. 6 that 60 a portion of the article is positioned over the beveled portion 135, thus providing a space between the article and the beveled portion for receiving the lower edge of the container. After the container has been moved over the article 65 into the position shown in Fig. 6, the rear end of the container is substantially opposite the center of the roller 105 and therefore the roller 105 is inoperative to move the container any further into the recess 125, and additional means 70 must be provided for this purpose.

This means comprises an auxiliary stripping member 136 pivoted at 137 to an arm 138 carried by a shaft 139 journaled in a bracket 140 supported by the table 1. A spring 141 is fastened to one end of the auxiliary stripping mem-

ber 136 and also to the arm 138 so as to rotate the auxiliary stripping member 136 against the adjustable stop 142, the adjustable stop being used to determine the operative position of the auxiliary stripping member 136. The shaft 139 5 also has an arm 143 rigidly secured thereto and this arm is connected by means of a link 144 to the pivoted arm 145, the arm 145 being pivoted at 146 to the hopper 7. A cam 147 is secured to the end of the shaft 9 and is adapted to engage a roller 148 on the arm 145 to thereby impart a rocking movement to the arm 145 as the shaft 9 rotates. A spring 149 secured to the bracket 29 and to the free end of the arm 145 normally holds the roller 148 in engagement with 15 the cam 147. As the arm 145 oscillates, a reciprocating movement is imparted to the link 144, and this in turn imparts a rocking movement to the shaft 139 and to the arm 138 and auxiliary stripping member 136. 20

A recess 150 is provided in the former 52 adjacent its forward edge so that when the auxiliary stripping member 136 is rotated in a clockwise direction as viewed in Fig. 6, the forward edge 151 of the stripping member will not strike the former 52 and will permit the former to engage the rear end of the container 121 which is located in the position shown in Fig. 6 when the auxiliary stripping member 136 is moving in a clockwise direction about its pivot, the motion of the stripping member 136 being so timed as to prevent engagement of the stripping member with the side of the container. The auxiliary stripping member is so adjusted by means of the adjustable stop 142 as to aline the rear edge of the 35 container substantially along the line 152, the abutment 153 acting as a means to aline the forward edge of the container. A stop 154 of smaller cross-sectional area than the container, provides a stop for the article to prevent the latter from being carried along with the container while permitting the container to be slipped over the stop so that a portion of the container protrudes over the article at both ends. 40

Before the bucket located at the position "A" 45 is carried to its next successive position, which is to the right as viewed in Fig. 6, it is necessary that the stop 154 be withdrawn. For this purpose I have secured the stops 153 and 154 to the upper end of a lever 155 which is pivoted at 156 50 to an angle bracket 156' secured to the upstanding bracket 157 mounted on the table 1. The bracket 157 also supports the bearing members 158 and 159 for the shafts 128 and 129, respectively. The arm 155 is actuated by means of a link 160 pivoted to the arm 155 and to the arm 62 pivoted to the shaft 61. The arm 62 carries a roller 161 which engages a suitable cam groove 162 in the cam 163. When the arm 62 is rocked by means of the cam 163, the arm 155 is also rocked about the pivot 156 and in timed relation to the movements of the buckets so that the stop 154 is withdrawn when the Geneva movement causes the chain to move the buckets from one 65 position to the next succeeding position. The arm 155 also carries an abutment 164 similar to the abutment 153, this abutment being for the purpose of alining the articles in the buckets prior to having the container placed thereover. 70 It will be noted that the abutment 164 extends inwardly a greater amount than does the abutment 153. This is for the purpose of spacing the articles a predetermined distance from the end of the container. 75

In Fig. 7, the auxiliary stripping member 136 is shown in its limiting forward position. While in this position the next succeeding blank 8 is in position beneath the former 52 and the folding members 91 and 92 have been moved vertically to fold the blank about three sides of the former 52 in the manner shown in Fig. 10. This brings the folding member 91 into the path of movement of the auxiliary member 136 on the latter's return movement and if the stripping member were rigidly secured to the arm 138, the same would strike the folding member 91 and thus interfere with the operation of the machine. However, due to the fact that the stripping member 136 is pivoted to the arm 138 and only yieldingly held against the abutment 142, the stripping member may rock about its pivot when the same strikes the folding member 91 (see Fig. 8), the spring 141 yielding sufficiently to permit the stripping member 136 to ride over the folding member 91 until the stripping member is clear of the folding member, whereafter the stripping member again occupies the normal position as shown in Fig. 6. By providing a stripping member constructed in the manner just described, it is possible to begin folding the next succeeding blank before the stripping member is brought back into its original position, thereby saving considerable time.

After the containers have been slipped over the articles in the buckets, the same are moved toward the right as viewed in Figs. 1 and 2, until they come to a position which I have designated as "B". In this position the ends of the tubular container are given a preliminary fold by means of a plurality of folding devices supported upon the slideable bar 165. These folding devices are best illustrated in Figs. 1, 2, 16, 17, 18, 19, and 20.

The sliding bar 165 is slidably mounted in the bearings 166 bolted to the brackets 167. On opposite sides of the endless conveyer which comprises the chains 122 and buckets 124, are provided two similarly designed folding devices. Each of these devices comprises a folding member 167 having a V-shaped notch 168 in the forward edge thereof, thereby forming a cam surface for a purpose which will appear later.

A bolt 170 is slideable in a bracket 171 rigidly mounted on the bar 165. This bolt 170 has a notched end portion forming two spaced-apart members 172 between which the folding member 167 is interposed as best illustrated in Figs. 16 and 19. The folding member 167 is held in position between the members 172 by the bolts 169. The members 172 have their outer surfaces curved to conform with the shape of the cylindrical guiding recess 173 in the bearing block 174 secured to the bar 165, thus forming a means for guiding the folding member 167 for longitudinal movement relative to the bar 165. In order to prevent the folding member 167 from rocking about an axis parallel to the bar 165, the recess 173 is arranged slightly below the upper surface of the bearing block 174 and a notch 175 engages the opposite surfaces of the folding member 167.

A pin 176 extends through the cam member 167 and carries the collars 177, the pin also being provided with keys 178 for preventing movement of the collars off the pin 176. Plates 179 are arranged along the opposite sides of the folding member 167 and have openings therein which extend over the pin 176 and also the pins 180, the latter pins being used to prevent movement of the plates about the longitudinal axis of the pin 176. Springs 181 are interposed between the collars 177 and the plates 179 and normally tend to

urge the plates 179 into engagement with the folding member 167. Each of these plates is shaped in a longitudinal direction in a manner substantially as shown in Figs. 17 and 18 with the cam surfaces 182 arranged at their rearwardly extending ends and with the creasing members 183 arranged at their forward container-engaging ends. The bracket 171 has a cam 184 formed integral therewith at the upper end thereof. A spring 185 surrounds the bolt 180 and is interposed between the bracket 171 and the folding member 167 normally urging the cam member away from the bracket 171 so that the head 186 of the bolt or pin 170 is in abutting relation with the bracket 171.

Since the bar 165 carries both of the folding devices, each of the folding devices is brought into engagement with the adjacent end of the container successively instead of simultaneously. However, by using the same bar to actuate both folding devices, a considerable saving results in the amount of mechanism necessary to fold the opposite ends of the container. Assuming that the parts are in the position shown in Fig. 18, I will proceed to describe the action of the folding devices in folding the opposite ends of the container.

The folding device shown at the left in Figs. 16, 17, and 18 is in position in Fig. 18 to move to the right and into engagement with the adjacent end of the next container as it is positioned at the position "B". As the folding device moves to the right in Fig. 18, the cam surface 168 at the forward edge thereof engages the upper and lower sides of the container and draws the upper side and lower side toward each other as best illustrated in Fig. 20. A stop 187 is formed integral with the folding member 167 and is adapted to abut against the plate 188 which also forms a support and alining means for the buckets 124. This stop comes into engagement with the plate 188 as soon as the cam surface 168 has folded the upper and lower sides of the container in the manner illustrated in Fig. 20, thereby arresting the forward movement of the folding member 167. However, the bar 165 continues its movement to the right, carrying with it the bracket 171, the spring 185 yielding to permit this relative movement between the bracket 171 and the folding member 167. As the bracket 171 moves toward the folding member 167 the cam 184 thereon engages the cam surfaces 182 on the plates 179, thus forcing the rear ends of the plates outwardly as shown in Fig. 17 and thereby bringing the creasing members 183 into engagement with the vertical sides of the container. This movement of the creasing members 183 is continued until the vertical sides of the container are folded between the folding member 167 and the creasing members 183 on the plates 179.

This folding operation produces folds or creases in the end of the container similar to that shown in Fig. 22 and the container tends to retain substantially the shape shown in Fig. 22 until further operations produce additional folds in the container ends. It will be understood, of course, that the folding device shown at the right of Figs. 16, 17, and 18 will come into engagement with the adjacent end of the container after the folding device shown at the left has been retracted into the position shown in Fig. 18, thereby producing a similar fold in this end of the container.

The bar 165 is connected by means of a link 189 to the pivoted lever 190. The arm 190 is

pivoted at 61 and is actuated by a suitable cam 191 on the shaft 11, it being understood that the cam 191 has a suitable cam groove therein which engages a roller on the arm 190.

5 After the container has been folded in a manner similar to that shown in Fig. 22, the same is moved to the glue applying position designated "C" (see particularly Figs. 25 to 30, inclusive). In this position a small quantity of glue is deposited in the creases or adjacent the creases 192 shown in Figs. 22, 27, 28, 29, and 30 and I have produced a novel means for depositing only a predetermined amount of glue at the position designated.

15 This means comprises the glue-boxes 193 located on opposite sides of the conveyer and the glue applying devices 194 which are suitably mounted so as to be simultaneously dipped into the glue contained in the glue-boxes 193 and 20 simultaneously brought into engagement with the opposite ends of the container, it being understood, of course, that it is not necessary that these glue applying devices be operated simultaneously, as they may be operated successively, 25 if desired. Each of the glue applying devices 194 has a plurality of notches 195 located at the forward edge thereof and spaced apart a distance substantially equal to the distance between opposed creases 192 in the ends of the container 30 and so arranged longitudinally on the devices 194 that each of the notches 195 substantially straddle the adjacent creases 192 when brought into engagement with the end of the container.

35 Each of the glue applying devices 194 is secured to one arm 196 of a bell crank which is rotatably supported on a shaft 197 and held against longitudinal movement by the collars 198. The other arm 199 of the bell crank is connected by means of a pin 200 to the actuating 40 arm 201 for rocking the bell crank about the shaft 197. The shaft 197 is moved vertically by means of a link 202 (see Fig. 1) connected to an arm 203 pivoted to the shaft 61 and actuated by a cam 204 engaging a cam roller 205 on the 45 arm 203, the cam roller operating within a suitable cam groove in the cam 204. When the actuating members 201 move the bell cranks so that the glue applying devices 194 are in the positions shown in Figs. 25 and 28, the shaft 197 is moved 50 downwardly into the dotted line position shown in Fig. 25, thus dipping the lower end of the applying devices into the glue contained in the glue-boxes 193. In order to prevent an excess amount of glue adhering to the glue applying devices 194, 55 I provide a scraper 206 for each glue applying device, these scrapers being located above the glue-boxes and in the vertical path of movement of the glue applying devices 194.

Each of the scrapers 206 has an opening 207 60 therein of substantially the same cross-sectional shape as the glue applying devices 194 so as the glue applying devices are raised vertically out of the glue-boxes, the excess glue is scraped from the sides of the glue applying devices and only a 65 very small portion of glue is retained in the notches 195 as best seen by an inspection of Fig. 27. Therefore, when the glue applying devices have been raised vertically and are moved into the positions shown in Figs. 26, 27, 29, and 30, 70 only small particles of glue are retained thereon and these are deposited in the creases or adjacent the creases 192 and in the manner best illustrated in Fig. 27.

75 Means is provided for rocking the glue applying devices about the shaft 197. This means com-

prises the actuating members 201 and the means for connecting these actuating members to the rotating shaft 11. A shaft 208 is rotatably mounted in a bearing in the frame 1 and is provided at its lower end with a crank arm 210. This crank 5 arm is pivotally connected to a link 211, which in turn is connected by means of a yielding lost motion connection 212 to the arm 213. This arm 213 is pivoted to the shaft 61 and carries a roller 214 which engages a suitable cam groove in the 10 cam 215. Rotation of the cam 215 rocks the arm 213 about its pivot and due to the connections just described, causes the shaft 208 to rock about its axis.

An arm 216 is secured to the upper end of the 15 shaft 208 and this arm is pivotally connected to the actuating member 201 which actuates the glue applying device shown at the right in Figs. 25 and 26, or the upper glue applying device shown in Fig. 2, so that rotation of the shaft 208 20 rotates the arm 199 about the shaft 197 and thereby moves the glue applying device just referred to from the position shown in Fig. 25 to the position shown in Fig. 26, and vice versa. In order to maintain proper operative connection 25 between the actuating means 201 and the pin 200, I make the pin 200 of considerable length and permit it to slide in a suitable opening in the end of the actuating means 201 so that as the shaft 197 moves up and down the pin 200 will 30 move up and down in the opening in the end of the actuating means 201.

The shaft 208 is also provided with an arm 217 at its upper end above the arm 216 and this arm 217 is connected by means of a link 218 to an arm 219 secured to the shaft 220. This shaft 220 also carries an arm 221, which in turn is connected to the actuating means 201 for the glue applying device shown at the left in Figs. 25 and 26, or at the bottom of Fig. 2. The connecting link 218 40 is so arranged as to actuate the arms 216 and 221 in opposite directions to thereby move the glue applying devices simultaneously toward and away from the opposite ends of the container (see Fig. 2).

45 After the glue has been applied to the creases 192, the container is given a transverse fold such as shown in Fig. 23, and thereafter by the same mechanism this fold is creased so as to produce a closed container such as that shown in Fig. 24. 50 As a final step in the closing of the container the transverse fold shown in Fig. 24 is given a curvature in the longitudinal direction of the fold such as illustrated in Fig. 25. The mechanism for producing these results is best illustrated in Figs. 55 31 to 38, inclusive.

After the glue has been applied to the container, the container is moved to the position "D" where the next step in the process is performed. In Figs. 31 to 38, inclusive, I have shown means for 60 folding one end of the container, it being understood that the opposite end of the container is folded by similar mechanism designated by similar reference characters in the drawings and therefore a description of the mechanism shown 65 in Figs. 31 to 38, inclusive, will be sufficient to describe the folding action which takes place at both ends of the container.

The arm 221 carried by the shaft 220 is provided at its forward end with a folding and creasing plate 223 and provided with a pin 224 at its opposite end. The plate 223 is provided with a substantially V-shaped notch 225 at its forward edge as is best illustrated in Figs. 31, 34, and 36. The pin 224 connects the actuating member 201 75

to the arm 221. As the shaft oscillates about its pivot it carries the arm 221 with it from the position shown in Fig. 36 to the position shown in Fig. 31, and then back again to the position 5 shown in Fig. 36.

A horizontal shaft 222 extends at right angles to the shaft 220 and this shaft carries an arm 225' to which is secured a folding and creasing member 226 in the manner best illustrated in 10 Figs. 36 and 38. The plate 226 is secured to the arm 225' by means of a bolt or cap screw 227. The shaft 222 carries a crank arm 228 at the rear end thereof as best illustrated in Fig. 2. This crank arm is connected by means of a link 15 229 to the pivoted arm 230 mounted on the shaft 61, the arm 230 being rocked about the shaft 61 by means of the cam 231 which engages the cam roller 232 on the arm 230 best illustrated in Fig. 1. The link 229 is connected to the arm 230 by 20 a lost motion connection similar to the parts 84, 85, and 86 illustrated in Fig. 3.

As the arm 230 is oscillated about its pivot, a reciprocating motion is imparted to the link 229, which in turn rocks the shaft 222 in timed relation 25 to the rocking movement of the shaft 220. The shaft 220 is rocked in timed relation with the shaft 222 so as to bring the plates 223 and 226 toward each other and against opposite sides of the end 233 of the container in the manner 30 illustrated in Fig. 31, the forward edge 234 of the plate 226 being arranged so as to force the opposite sides of the end portion 233 toward each other and into the V-shaped notch 225 in the plate 223 with portions of the end 233 lying along 35 the two sides of the V-shaped portion and between the plates 223 and 226, thus producing a partial fold in the end 233, this fold corresponding to the fold illustrated in Fig. 23.

Mounted on one side of the bracket 157 is a 40 bar 235 carrying a pivot pin 236 at its upper end. This pivot in turn supports an arm 237 provided with two forwardly projecting fingers 238 (see Fig. 33) which lie within the slots 239 provided in the arm 221, the slots 239 being sufficiently deep 45 as illustrated by the dotted lines in Figs. 31 and 36, and full lines in Fig. 34 to permit free movement of the forwardly projecting portions 238 about the pivot 236 without interfering with the movement of the arm 221. The arm 237 is 50 provided with a pin 240 which forms a pivot for the link 241, the other end of the link 241 having a slot 242 through which an extension 243 on the pin 224 is adapted to extend. The extension 243 also provides a pivot for the link 244, this latter link serving as a means for holding the link 241 from movement longitudinally of the extension 243. A pin 245 extends through the extension 243 and serves to hold the link 244 on the extension 243. A spring 246 has one end there- 55 of secured to the extension 243 and the other end thereof to a pin 247 on the under side of the connecting link 241 and adjacent the pivotal connection 240 between the link 241 and the arm 237. The spring normally tends to hold the extension 60 243 off the pin 224 in the end of the slot 242 nearest the pin 247 unless some other force is operative to extend the spring 246 and move the extension toward the opposite end of the slot.

When the folding and creasing plates 223 and 70 226 are moved toward each other, the forward rounded end portion 248 will be moved into a position between the opposed faces of said creasing members. However, the creasing member 226 strikes the portion 248 of the arm 237 and 75 moves this arm in a counter-clockwise direction

as viewed in Fig. 31 about its pivot, and this in turn moves the link 241 in such a direction as to increase the distance between the pivotal connection 240 and the extension 243 on the pin 224, thus extending the spring 246 and moving the extension 243 toward the opposite end of the slot. In other words, the slot is for the purpose of permitting a certain amount of lost motion between the pivot 240 and the extension 243.

By the arrangement just described, when the 10 creasing plates 223 and 226 are moved toward each other, the end of the container located at the position "D" is folded so that it is substantially L-shaped in cross-section as viewed in Fig. 31, the portion 248 of the arm 237 having 15 been forced out of the way by means of the folding plate 226. Immediately after this fold is produced, the folding and creasing plate 226 is moved away from the plate 223 and while the container remains in the same position, the 20 creasing plate 223 is again brought back into the same position as shown in Fig. 31, but the action of the plates 223 and 226 is different than that previously described with reference to producing the L-shaped folds shown in Fig. 31 as will be 25 seen by an inspection of Figs. 34 and 35.

In this operation, the portion 248 of the arm 237 is again carried between the creasing plates 223 and 226 and has a tendency to move the free end of the fold shown in Fig. 31 into the position shown in Fig. 34 so that as the folding and creasing plate 226 approaches the folding and creasing plate 223, the outer side and not the inner side of the free portion of the fold is engaged by the creasing device 226 and this creasing device 226 will fold the free end of the fold against the other portion thereof and in the manner shown in Fig. 35, the portion 248 on the arm 237 being thrown out of position as before. This operation produces a crease in the folded portion and after this operation, the container has the appearance of the container illustrated in Fig. 24, and the container is ready for the last operation of producing a longitudinal curvature in the folded portion.

The means for producing a longitudinal curvature in the folded portion is best illustrated in Figs. 31, 32, 36, 37, and 38. A shaft 249 is rotatably mounted in the bearing 250 secured to one side of the bracket 157 and has an arm 251 secured to the lower end thereof, a link 252 connecting the arm 251 to an arm 253 secured to the shaft 220 and rotatable therewith. The shaft 249 has a plate 254 secured to the upper end thereof as best illustrated in Figs. 31 and 38, and this plate has a transverse convex curvature such as that illustrated in Fig. 32. A plate 255 has a transverse curvature which is substantially a counterpart of the curvature of the opposed surface of the plate 254 and this plate 255 is carried by means of an arm 256 rotatably mounted upon the shaft 249.

The arm 244 having the screws 258 for adjusting the effective length of the arm 244 is pivoted at 259 to the arm 256, and also is pivotally connected to the extension 243 as previously described. It will be noted that the links 252 and 244 are both connected to arms secured to the shaft 220 so that rotation of the shaft 220 moves the links in opposite directions and thereby causes the plates 254 and 255 to be moved away from each other and toward each other in unison.

As the containers are brought into the position indicated at "E" in Figs. 31 and 36, the plates 75

254 and 255 are spaced apart in the manner illustrated in Fig. 36 and are thereafter brought into opposed relation with each other on opposite sides of the folded portion at the end of the container in the manner illustrated in Fig. 31. Due to the fact that the opposed faces of the plates 254 and 255 are curved, the folded portion of the container is given a like curvature when the plates 254 and 255 are brought normally into engagement therewith. In order to insure that the fold will lie properly between the plates 254 and 255, I provide a pivoted finger 260 pivoted at 261 to a bracket 262 secured to one side of the bearing 250 as best illustrated in Fig. 38. A spring 263 normally tends to rotate the finger 260 in a counter-clockwise direction as viewed in Fig. 31, and into engagement with the bottom of a recess 264. The finger 260 is provided with a cam surface 265 on the side thereof adjacent the bottom of the recess and this cam is so shaped as to force the forward edge of the finger 260 into engagement with the free end of the folded portion of the container in the manner shown in Fig. 37 and just prior to the engagement of the plates 254 and 255 with the opposite sides of said folded portion. This prevents the free end of the folded portion from being folded improperly when the plates 254 and 255 come into engagement with each other, it being obvious that if the free end were extending at right angles to the other portion of the fold then the tendency for the plates would be to crumple the free end in a direction transverse to the longitudinal crease in the fold. It will be noted that the cam surface 265 rides on the bottom of the recess 264 at all times. The pin 261 has an adjustable collar 262' to which one end of the spring 263 is secured. By adjusting the angular position of the collar 262' the tension of the spring 263 is increased or decreased, as desired. The other end of the spring engages the arm 268.

After the operation just described, the article is completely enclosed within the container and the container has the shape illustrated in Fig. 5, the curvature in the fold tending to hold the two portions of the fold in abutting relation with each other, or at least preventing any substantial amount of movement of the portions of the fold away from each other. The container with the enclosed article is now ready to be enclosed within a suitable carton, if desired, or merely placed on the market in the container shown in Fig. 5.

55 The containers are moved from the position "E" to the position "F" which is best illustrated in Fig. 1, the position "F" being a position substantially in a horizontal plane through and to the right of the shaft 129. An ejector bar 266 carried by an arm 267 is adapted to reciprocate in a direction transversely of the movement of the conveyor and as each bucket is positioned at the position "F" the ejector bar 266 moves into the recess 125 and ejects the wrapped article out of the recess and onto a suitable support 268 provided with the flanges 269. The articles may then be removed from the support 268 by hand or they may be discharged from the support 268 onto another machine, or additional mechanism supplied on the same mechanism, which other machine or additional mechanism is provided for the purpose of enclosing the wrapped article in a suitable carton, but since the present invention is not concerned with this step in the proc-

ess of wrapping the article, the same has not been illustrated in the drawings.

The arm 267 is carried by a rod 270 slidably mounted in suitable bearings in the frame and provided at its rear end (see Fig. 3) with a bracket 271 rigidly secured thereto and having a portion 272 slidably engaging a fixed guide rod 273 so as to prevent turning of the rod 270 about its pivot. A link 274 is pivotally connected to the bracket 271 and also to an arm 275 rotatably mounted on the shaft 61, the arm 275 being rocked about the shaft 61 by means of a cam 276 which engages a cam roller 277 on the shaft 61 (see Fig. 1).

A means is provided for holding the containers 15 in fixed relation to the buckets 124 while the containers are at the positions "B", "C", "D", and "E". This means comprises a bar 278 carried by the arms 279 of a pair of similarly shaped bell cranks, the other arms 280 of which are pivotally connected to the bar 281. The bar 281 is pivotally connected at 282 to the arm 283 rotatably mounted on the shaft 275 and this arm is rocked about its pivot by means of a cam 284 secured to the shafts 16, the cam 284 being provided with a suitable cam groove 284' in which the roller 285 on the arm 283 is adapted to ride. The bar 278 carries the outwardly extending arms 286, 287, 288 and 289 located above the positions "B", "C", "D", and "E", respectively. Each of the arms 286, 287, 288 and 289 carries a plurality of yieldable members 290 and these yieldable members are adapted to engage the upper surfaces of the containers while they are located at the aforementioned positions and assist in steadyng the containers while the various operations are being performed at these positions.

The operation of the device is as follows:

The blanks 8 are inserted in the hopper 7 and fed out of the hopper between the rollers 15 and 16, whereafter the glue is applied to one edge of the blanks by means of the gluing wheel 37. The blanks are next fed between the rollers 48 and 49 in the manner described and after the blanks have been fed forward as far as possible by means of these rollers, the alining means 55 engages the rear edges of the blanks and feeds them into alined position beneath the former 52.

After the blanks have been positioned beneath the former 52, the blanks are formed into hollow 50 tubular containers by means of the folding plates 91, 92, 98, and 100 and the roller 105 strips the containers off the former 52 and partially over the articles within the pockets 125. The auxiliary stripping member 136 is then moved into engagement with the rear edge of the container and moves the container all the way over the article and alines the container with respect to the pocket and article.

The next operation consists in producing a 60 preliminary fold in each end of the container by means of the folding members 167 and folding and creasing members 183, thus producing a container such as that shown in Fig. 22. The rod 165 actuates each of the folding members 167 and 65 their respective folding and creasing members 183 in succession instead of simultaneously while at the position indicated as "B" in the drawings.

The containers are next moved to the position "C" where the glue applying devices 194 deposit 70 a small amount of glue in the creases 192, the scrapers 207 acting to scrape the excess glue off the glue applying devices 195. The glue applying devices each have a motion of rotation, as well as one of translation, the former movement being 75

for the purpose of applying the glue to the creases and the latter being for the purpose of dipping the glue applying devices into the glue contained in the glue-boxes.

5 The containers are next moved to the position "D" in which the opposite ends of the container are each given a substantially double fold by means of the creasing plates 223 and 226, the forward portion 248 of the arm 237 acting as a 10 means to insure that the free end of the fold is turned in the proper direction before the fold is completed.

The articles are next moved to the position "E" where the folds are given a longitudinal curvature by means of the plates 254 and 255, and finally the articles are moved to the position "F" where they are ejected from the buckets 124 by means of the ejector 266, the ejector moving the articles onto the support 268.

20 I wish to have it understood that while I have illustrated a machine for wrapping tooth brushes, the same type of machine may be used for wrapping other articles such as tubes for shaving cream, small vials and brushes. In other words, 25 my invention is not limited to wrapping the particular type of article illustrated in the drawings.

I also wish to have it understood that while I have described a machine which contemplates using wrappers of comparatively thin material 30 my invention is capable of being embodied in a machine which uses cardboard or the like which may, if desired, be scored to facilitate the making of the folds. Furthermore it is obvious that I may use cartons which are formed in other ways 35 and which are slipped over the articles in the pockets, the flaps of the cartons being tucked in or otherwise folded to close the carton. It is not necessary that glue be used to seal the container but it is preferable to do so.

40 Obviously those skilled in the art may make various changes in the details and arrangement of parts without departing from the spirit and scope of the invention as defined by the claims hereto appended, and I wish therefore not to be 45 restricted to the precise construction herein disclosed.

Having thus fully disclosed an embodiment of my invention, what I desire to secure by Letters Patent of the United States is:

50 1. Wrapping apparatus comprising a form, means for moving a sheet of wrapping material to a position adjacent said form, means for applying an adhesive to said material, means for wrapping said material about said form with 55 opposite edges thereof in overlapping relation and with said glue interposed between said edges, and means for simultaneously moving said container formed on said form off said form and for pressing said overlapping edges toward each 60 other to seal the same together.

2. Wrapping apparatus comprising a form, means for moving a sheet of wrapping material to a position adjacent said form, means for applying an adhesive to said material, means for 65 wrapping said material about said form with opposite edges thereof in overlapping relation and with said glue interposed between said edges, and means for simultaneously moving said container formed on said form off said form and for 70 pressing said overlapping edges toward each other to seal the same together, said last-mentioned means comprising a rotating roller adapted to frictionally engage said edges.

3. A wrapping machine comprising a form, 75 means for feeding paper to a position adjacent

said form, means for applying glue to one edge of said paper, means for forming said paper about said form to make a hollow container, the opposite edges of said paper overlapping on said form with said layer of glue between said edges, 5 and a rotating element movable into a position to engage one of said overlapping edges to press said edges together as said rotating element moves said container off said form.

4. A wrapping machine comprising a form, 10 means for feeding paper to a position adjacent a form, means for applying glue or the like to said paper, means for forming said paper into a container about said form, a rotatable roller with resilient friction material on the surface thereof, 15 means for moving said roller so as to engage said container and move said container off said form, and means for positioning an article in the path of movement of said container so that the latter will move over said article. 20

5. A wrapping machine comprising means for forming a wrapper into an open-ended container on a form, means for moving said container part of the way off said form and over the article to be wrapped, and additional means adapted 25 to engage the rear end of said container and move said container completely off said form and over said article.

6. Means for moving a container off a form and over an article comprising a member moving in a fixed path, and a second member mounted on said first member and adapted to engage said container, said second member having a normal path of movement which is fixed but 30 which path is automatically varied if and when 35 said second member strikes an object which will not permit said second member to continue its movement in said normal path.

7. A wrapping machine comprising a former, 40 a moving member adjacent said former, folding means for wrapping a piece of wrapping material about said former to make an open-ended container, means for positioning an article adjacent said container, means on said moving member adapted to engage and move said container off said former and over said article, and yielding means for permitting said last-mentioned means to yield if and when it strikes said folding means.

8. A wrapping machine comprising a former, 50 a moving member adjacent said former, folding means for wrapping a piece of wrapping material about said former to make an open-ended container, means for positioning an article adjacent said container, means on said moving member adapted to engage and move said container off said former and over said article, and yielding means for permitting said last-mentioned means to yield if and when it strikes said folding means, said means on said moving member being also adjustable to predetermine thereby 60 the amount of movement which will be given thereby to said container.

9. A wrapping machine comprising means for moving an open-ended container over an article, 65 and mechanism for folding said open ends comprising means for engaging the material of said container at opposed points and for drawing said portions toward each other, and means for engaging a portion of the material of said container 70 at points spaced from said first-mentioned points and for moving said last-mentioned portions toward each other.

10. A wrapping machine comprising means for positioning a tubular open-ended wrapper over 75

an article to be wrapped, a member having two substantially flat sides, a cam surface on said member between said two sides, means for moving said member toward and into engagement with an open end of said wrapper with said cam surface engaging the outer surface of said wrapper at spaced substantially opposed points, said cam drawing the material of opposite sides of said wrapper toward each other, and additional means for moving the portions of said wrapper opposed to said substantially flat sides firmly against said flat sides, whereby to crease said wrapper before said member having said cam surface thereon is moved out of operative position.

11. A wrapping machine comprising means for positioning a tubular open-ended wrapper over an article to be wrapped, a member having two substantially flat sides, a cam surface on said member between said two sides, means for moving said member toward and into engagement with an open end of said wrapper with said cam surface engaging the outer surface of said wrapper at spaced substantially opposed points, said cam drawing the material of opposite sides of said wrapper toward each other, and additional means for moving the portions of said wrapper opposed to said substantially flat sides firmly against said flat sides, whereby to crease said wrapper before said member having said cam surface thereon is moved out of operative position, said additional means being operable after said cam member has engaged said wrapper and started said first opposed portions of said wrapper toward each other.

12. A wrapping machine comprising means for positioning an article in an open-ended container, a member having a substantially V-shaped notch therein adapted to engage said container at opposed points on the outer periphery of the open end of said container longitudinally of the end thereof, and means for moving said member toward said open end of said container in a manner to cause the simultaneous engagement of the sides of said substantially V-shaped notch with opposed points on said container to thereby draw the opposite sides of said open end toward each other, and means engageable against the sides of the V-notched member while the latter is in operative position to crease the container walls thereagainst.

13. A wrapping machine comprising means for positioning an article in an open-ended container, a member having a substantially V-shaped notch therein adapted to engage said container at opposed points on the outer periphery of the open end of said container, means for moving said member toward said open end of said container in a manner to cause the simultaneous engagement of the sides of said substantially V-shaped notch with opposed points on said container to thereby draw the opposite sides of said open end toward each other, and spaced plates for engaging the sides of the said open end at points other than those first mentioned, said plates being adapted to move the yet unfolded portions of said open end toward each other and against said member having said substantially V-shaped notch therein.

14. A packaging machine comprising means for positioning an article within a hollow package having an open end, means for folding the edges of the material adjacent said open end to form

a crease, means for thereafter depositing a small amount of adhesive in said crease, and means for thereafter pressing the portions of said material adjacent said crease together to seal the same.

15. A packaging machine comprising means for positioning an article within a hollow package having an open end, means for folding the edges of the material adjacent said open end to form a crease, means for thereafter depositing a small amount of adhesive in said crease adjacent the marginal edge of said open end, and means for thereafter pressing the portions of said material adjacent said crease together to seal the same.

16. A packaging machine comprising means for enclosing an article in an open-ended package, and means for applying glue at selected places about the marginal edge of said open end comprising a member adapted to retain glue in definite positions thereon and means for moving said member to bring said glue at said selected positions into engagement with said marginal edge.

17. A packaging machine comprising means for enclosing an article in an open-ended package, means for forming a crease in said package adjacent the marginal edge of said open end, and means for depositing a small amount of glue in said crease comprising a member having means for retaining a desired quantity of glue thereon and means for moving said member so as to bring said glue into a position in which the glue contacts with the surface of said crease.

18. A packaging machine comprising means for enclosing an article in an open-ended container or the like, means for forming a crease in the open end of said container, means for depositing a small amount of adhesive in said crease, and means for moving the opposed inner surfaces of said wrapper which lie adjacent said crease toward each other.

19. A packaging machine comprising means for forming creases in a package adjacent the end thereof, and means for depositing an adhesive on said package at said creases, comprising a member adapted to be dipped into an adhesive in a vessel, means for removing substantially all of said adhesive from said member except small quantities thereof arranged on said member in substantially the same relation to each other as said creases bear to each other and means for moving said member into engagement with said package with said glue arranged in close proximity to said creases.

20. Mechanism for sealing the end of an open-ended container comprising a pair of movable members having mating angularly disposed surfaces, means for forming a flat fold in said package, means for moving said members into engagement with opposite surfaces of said fold so that said fold is bent at an angle to produce a main portion and an angularly extending portion, yielding means movable into a position between said members when said members are moved apart and for moving said angularly extending portion toward said main portion while said members are apart, and means for again bringing said members toward each other to move said angularly extending portion against said main portion to produce a crease therebetween and thus form a double fold.

21. A container sealing device comprising means for forming a fold at one end of said container and members having substantially

- complementary opposed faces of a shape to distort said fold when moved into engagement therewith, said members having their substantially complementary surfaces movable into engagement with opposite surfaces of said fold. 5
22. In a packaging machine, the combination with means for conveying articles along a defined path, of means for positioning open-ended containers over said articles, means for creasing the 10 ends of said containers, means for depositing a small quantity of adhesive adjacent said creases after the same are formed, and means for folding said ends to cause said glue to hold the sides of said folded ends together. 15
23. In a wrapping machine, means for enclosing articles within an open-ended container, means for moving said containers to a folding position, means for producing a partial fold at said folding position, said partial fold including a creased portion, means for moving said containers to a glue applying position, means for applying glue to said creased portion of said containers, means for completing said fold, and means for crimping the end of said fold. 20
24. A wrapping machine, comprising a cam-shaped member for drawing the opposite sides of an open-ended container toward each other, and means for moving the remaining portions toward said cam-shaped member after said cam member has drawn said opposite sides inwardly but while said latter portions are extending away from the article being wrapped, said last-mentioned means being operable to crease said folded end and as it moves out of engagement with said folded end, 30 and said cam-shaped member being movable out of engagement with said folded end before said means moves out of engagement therewith. 35
25. A packaging machine comprising means for moving open-ended containers to a predetermined position, a bar movable transversely to the path of movement of said container, cam members yieldingly held on said bar, stop members on said cam members, plates on opposite sides of said cam members and yieldingly held thereagainst, 40 and a second cam means for moving said members against the action of said yielding means. 45
26. A packaging machine comprising means for moving open-ended containers to a predetermined position, a bar movable transversely to the path of movement of said container, cam members yieldingly held on said bar, stop members on said cam members, plates on opposite sides of said cam members and yieldingly held thereagainst, 50 and a second cam means for moving said members against the action of said yielding means, said bar being movable to bring said cam members and plates successively into engagement with the open ends of said container to fold the same. 55
27. A packaging machine comprising means for forming a flat fold at the end of an open end of a container, means for doubling said fold upon itself, means for crimping the double fold so that the crease in the fold is other than in a straight line to cause both portions to be maintained substantially in engagement with each other, and a member to preliminarily engage and move the portions of said double fold together before being engaged by said last-mentioned 65 means. 70
28. Means for folding the open end of a container comprising a member having a substantially V-shaped notch therein adapted to receive the open end of a container with the opposite 75 sides of said notch engaging the outer opposite edges of said open end to draw the same toward each other as said member moves toward and into engagement with said open end, means for moving a container and said member toward each other to thereby move the sides of said notch against the opposite outer sides of said open end, and means for thereafter moving the intermediate portions of said open end toward each other and against said member. 5
29. Means for folding the ends of a tubular 10 wrapper comprising a member positioned adjacent one end of said tubular wrapper and having portions thereof shaped for substantially line contact with the opposite sides thereof, means for moving said member toward the adjacent end 15 thereof in a direction substantially in alignment with the open end of said wrapper so that said portions are brought into contact with said wrapper in the manner set forth, said members acting to draw portions of the sides engaged toward each other, and additional members for moving said portions of said open end intermediate said first portions toward and against opposite sides of said first mentioned member while said first mentioned member remains in position so as to form a crease in said wrapper to cause said wrapper to thereby maintain a shape substantially in conformity with the shape given thereto by said members. 20
30. In a wrapping machine, the combination with means for enclosing an article in a tubular container, of means for creasing the ends of the container, means thereafter for applying a small quantity of adhesive only at the portions of said wrapper adjacent said creases, and means for closing the ends of said wrappers to bring the surfaces adjacent said creases toward each other so that the glue will cause said surfaces to adhere to one another and thus seal the open ends. 35
31. In a wrapping machine, the combination with means for enclosing an article in a tubular container, of means for creasing the ends of the container, means thereafter for applying a small quantity of adhesive only at the portions of said wrapper adjacent said creases, means for closing the ends of said wrappers to bring the surfaces adjacent said creases toward each other so that the glue will cause said surfaces to adhere to one another and thus seal the open ends, and means for thereafter putting a transverse fold in each of said open ends to assist in retaining said open ends in engagement with respect to each other and prevent strain on the adhesive holding said ends together, the said crease being formed while the portions of the wrapper are extending from the article. 40
32. A device as claimed in claim 31 in which there is a means provided for shaping said transverse fold so that the crease formed by the fold is other than in a straight line whereby the unfolding of the fold is substantially prevented. 50
33. In a wrapping machine, the combination of means for wrapping an article in a tubular container, and means for closing the open end of said container including means for forming creases in said wrapper at predetermined distances from each other, and means for applying an adhesive to the surfaces adjacent said creases comprising a glue applicator having glue retaining portions thereon spaced from each other distances equal to the spaces between said creases, said applicator being movable to bring said glue applying portions into juxtaposition with respect to said creases. 65
- 70
- 75

34. In a wrapping machine, the combination with a form substantially of the shape desired for a tubular container, means for wrapping a blank entirely about said form to form a tubular container thereon, means for moving the container off said form after it has been formed to a loading position, an arm for stripping said container off said form, said form having a recessed side to permit said arm to move inwardly beyond the outer confines of said form whereby the end edge of said container may be engaged thereby, means for partially moving said container off said form after it is formed, and means for periodically moving said arm into said recessed portion behind the end of said container after said container has moved partially off said form, said arm continuing its movement until after said container has been entirely removed from said form.
35. A device as set forth in claim 34 which includes a movable folder for folding the wrapper against the side of the form which has the recessed portion, said folding means being movable over said recessed portion and intersecting the path of said arm after said arm has moved said container off said form and in which the said arm reciprocates and is yieldingly mounted whereby as the same moves back into a position to engage the end of the next container, it may move out of its normal path of movement as it strikes said folding means.
36. A packaging machine comprising means for forming a tubular container, means for enclosing an article within said container, and means for thereafter sealing the open ends of said container comprising means for folding the ends of said container back upon themselves, and means for curving said portions which are doubled back in the same direction as the crease, whereby the crease is given a substantially curved form which prevents the material adjacent said crease from unfolding.
37. The method of enclosing articles in a container comprising the steps of forming a container out of a blank, moving the container off the former and over the article, placing glue on the opposed end edges of said container after the container is moved over the article, and producing a double fold in said edges while the same extend outwardly from the article being wrapped.
38. The method of enclosing articles in a container comprising the steps of forming a hollow container, transferring the container directly from the former over the article to be enclosed in said container directly after said container is formed, producing a double fold in each of the opposite ends of said container, and curving said folds in the direction of one of its creases for preventing the unfolding of said fold.
39. The method of wrapping which includes the steps of creasing said wrapper to bring adjacent portions of the surface of said wrapper into opposition with each other, and applying glue only to the portions of said wrapper adjacent said creases after the creases have been formed.
40. In a wrapping machine, the combination with means for moving a series of articles along a predetermined path, and an abutment arranged adjacent said path at a predetermined position in said path to act as an abutment for said articles to prevent the same from moving transversely to said path of movement, means for moving a container over said article as it arrives at said position, said abutment preventing the movement of the article as said container moves over said article, and said abutment having an outer contour which is of a shape and size sufficient to permit its entry into the end of said container as said container moves over the article whereby said container extends beyond that end of said article adjacent said abutment, and means for moving said abutment periodically into and out of its operative position whereby it will be in position to prevent the movement of said articles as said containers move over said articles and is out of operative position as said containers with the articles enclosed therein move on to a subsequent position in said path of movement.
41. In a wrapping machine, the combination with means for moving a series of articles along a predetermined path, and an abutment arranged adjacent said path at a predetermined position in said path to act as an abutment for said articles to prevent the same from moving transversely to said path of movement, and means for moving a container over said article as it arrives at said position, said abutment preventing the movement of the article as said container moves over said article, and said abutment having an outer contour which is of a shape and size sufficient to permit its entry into the end of said container as said container moves over the article whereby said container extends beyond that end of said article adjacent said abutment.
42. An article wrapping apparatus comprising a hopper for holding a plurality of wrapper blanks, a form, means for feeding said blanks from the hopper to said form, wrapping elements for wrapping one of said blanks about said form to form a container, and means for moving said container relative to the article to be wrapped so as to position said container over said article immediately after said container is formed from said blank.
43. Mechanism for folding the open end of a container comprising means movable toward the container position and in a direction substantially in alinement with the longitudinal axis of said open end, said means comprising a pair of members engageable with opposed points on the container end and operable to draw said points toward each other, and a pair of members engageable with the opposed portions on said container end intermediate the first engaged points and operable to crease said portions against said first named pair of members.

MICHAEL J. MILMOE. 65
